UNITED STATES PATENT OFFICE.

BERNARD DONAHUE, OF YONKERS, NEW YORK.

PIPE AND NUT WRENCH.

SPECIFICATION forming part of Letters Patent No. 414,799, dated November 12, 1889.

Application filed October 6, 1887. Serial No. 251,629. (No model.)

To all whom it may concern:

Be it known that I, BERNARD DONAHUE, a citizen of the United States, residing at Yonkers, in the county of Westchester and State of New York, have invented new and useful Improvements in Pipe and Nut Wrenches, of which the following is a specification.

This invention has for its object to provide a pipe and nut wrench having a jawed sleeve adjustable for nuts and pipes of varying sizes or diameter, and a novel movable or self-adjusting-toothed pawl for gripping and turning pipes of varying diameter without the possibility of the wrench slipping on the pipe by the contact-point of the pipe with the pawl falling between the points of two teeth.

The object of my invention I accomplish by the combination of devices hereinafter described and claimed, reference being made to the accompanying drawings, in which—

Figure 1 is a longitudinal central sectional view of an adjustable nut and pipe wrench embodying my invention; Fig. 2, a transverse sectional view on the line xx , Fig. 1; Fig. 3, a detail perspective view of the diagonally-toothed movable grip-pawl for the adjustable jawed sleeve, and Fig. 4 a similar view showing a modification of the pawl.

In order to enable those skilled in the art to make and use my invention, I will now describe the same in detail, referring to the drawings, wherein—

The numeral 1 indicates a solid wrench-shank rectilinear in cross-section and provided at one end with two stationary jaws, the one 2 having an inverted-V-shaped or angular recess 4 for receiving a portion of a pipe to be turned, and the other one 3 having a straight plane face 5 to bear upon part of an ordinary screw-nut to be screwed up or unscrewed. The adjustable jawed sleeve consists of a sleeve 7, loosely engaged at one end by a rotating screw-nut 6, mounted on the screw-thread 22 of the wrench-shank, said sleeve having at the other end the opposite jaws 8 and 8^a, the latter to coact with the stationary nut-jaw 3 and the former to carry the movable grip-pawl 12 to coact with the recessed pipe-jaw 2. The jawed sleeve is adjustable to and from the stationary jaws through the medium of the rotating screw-

nut for the purpose of adapting the wrench to operate practically and perfectly on nuts and pipes having a wide range of difference in diameter or size. The grip-pawl 2 is formed with a depending square or rectilinear shank 14, loosely fitting in a rectilinear cavity 9 in the jaw 8, the said cavity being of substantially the same width as the pawl-shank, but of greater length than the same to permit the pawl to move to and from the edge of the wrench-shank 1, and the pawl-shank has a transverse slot 19, through which passes a detachable pin 20 for detachably connecting the pawl to its carrying-jaw, while permitting the pawl to move as described. The reduced shank of the pawl provides the latter with side flanges 16, which, resting on the straight face 17 of the jaw 8, gives the pawl a base of support on the said jaw equal to the width thereof, thereby strengthening and preventing lateral twisting of the pawl when in use. The movable or self-adjustable pawl has pointed teeth 13 extending across its face obliquely to a line taken lengthwise through the pawl-body, and the latter is tapering, so that the oblique teeth, although of the same size themselves, recede in height with reference to the face of the movable jaw 8 from the outer end of the pawl toward the wrench-shank, as before stated. The line of direction of these oblique teeth is obliquely outward from the inner end of the pawl, or, rather, in an oblique direction away from the wrench-shank. By this construction of the pawl the pipe when grasped will have bearings in oblique lines upon several different teeth—say four teeth of the pawl if the pipe be large—and consequently it is impossible for the pawl to slip from one tooth to another when gripping a pipe, as occurs when the teeth extend across the pawl at right angles to its side, as in the latter case the contact between the pipe to be turned and the pawl frequently falls between two straight teeth, especially if the pipe be of small diameter, and consequently the pawl slips upon the pipe, and the wrench is rendered very objectionable if not practically useless.

In my construction of pawl several different teeth will engage the pipe in oblique lines, thereby holding said pipe at as many and dis-

tinct points, rendering it impossible for the pawl to slip on the pipe by the contact falling between two teeth. The oblique teeth may all extend in the same direction, as in Fig. 3, or they may extend in opposite directions from the sides and meet at the center of the pawl, as shown in the modification, Fig. 4; but in either event they must run in an oblique direction away from the inner end of the pawl or away from the wrench-shank. The construction and arrangement of the pawl with oblique or diagonal teeth, as explained, provide a more efficient gripping action than where the teeth extend across the teeth at right angles to the sides of the pawl, and, besides, in the latter construction, when the contact falls between two straight teeth, the pawl will slip on the pipe from one tooth to another, as before stated, whereas in the oblique or diagonal arrangement of the teeth this slipping is impossible. By constructing the face of the pawl tapering, so that it inclines downward toward the wrench-shank, with the teeth constructed and arranged as described, it will be moved smoothly and evenly outward until the pipe is centered in the angular recess of the pipe-jaw 2, as hereinafter explained.

The operation of the wrench is somewhat similar to ordinary wrenches in which a serrated pawl slides on an incline at the end of the shank or body. If the pipe be inserted between the stationary pipe-jaw 2 and the pawl, and the jawed sleeve 7 be adjusted toward said pipe-jaw, the pipe will be forced along the inner slope of the wall of the recess 4, and consequently said pipe will move laterally in a direction away from the wrench-shank, and at the same time the pipe, acting on the pawl, will force the latter outwardly until the pipe is centered in said recess 4, and thus the pawl automatically moves and adjusts itself to the pipe and to pipes of varying diameter, and is always brought into the proper position for its grip action. When the wrench is turned to rotate the pipe, the oblique teeth on the pawl grip the pipe at several different points in oblique lines and the pawl has a tendency to move inward to secure binding action. When the wrench is turned back to obtain a new purchase, the pawl moves outward away from the wrench-shank to release the grip, and so on until the pipe is turned the requisite extent. The nut-jaws operate on varying-sized nuts in the ordinary manner, the jawed sleeve being ad-

justable to increase or diminish the space between the respective jaws.

Prior to my invention in all adjustable wrenches—that is, wrenches having adjustable jaws to operate on nuts and pipes of varying size in diameter—the teeth of the grip-pawl have extended in lines at right angles to the sides of the pawl, or to a line taken lengthwise through the pawl from its inner end next the wrench-shank to its outer end farthest from the wrench-shank. The wrench having an adjustable jawed sleeve for operating on nuts and pipes of different diameters is the one most largely demanded by the trade, and a self-adjusting pawl on the jawed sleeve to alternately grip and release pipes of varying diameter is the kind most largely used because of its automatic action; but so far as I am aware no wrench of the kind mentioned has ever heretofore been provided with a self-adjusting pawl having oblique teeth so arranged that even when operating the smallest diameter of pipe made the contact between the pipe and the pawl can never fall between the points of two teeth, and thereby render it practically impossible for the pawl to slip on the pipe if the wrench be properly used, even if the teeth be dull from use.

A wrench having no adjustable jaw has little demand in the market, for the reason that a nut or pipe cannot be properly seized to turn it if tight. Its use is so restricted as to render it of but little value, and it becomes necessary to bodily move the wrench away from a pipe when a new purchase is to be taken.

What I claim is—

The combination, with the adjustable duplex jawed sleeve of a wrench for operating upon pipes and nuts of varying diameter, of a self-adjusting grip-pawl having on its back the elongated slotted shank fitting into a recess formed in the jaw of the sleeve and having lateral side flanges to give the pawl a base of support substantially equal to the width of the face of the jaw and provided with teeth extending across its face directly opposite the elongated shank in oblique lines to prevent the pawl slipping on pipes when acting thereon, substantially as described.

In testimony whereof I affix my signature in presence of two witnesses.

BERNARD DONAHUE.
